UNITED STATES PATENT OFFICE.

FRANZ YOKEL, OF MERIDEN, CONNECTICUT, ASSIGNOR TO THE MERIDEN BRONZE COMPANY, OF SAME PLACE.

DESIGN FOR A TABLE-TOP.

SPECIFICATION forming part of Design No. 21,722, dated July 19, 1892.

Application filed June 20, 1892. Serial No. 437,381. Term of patent 3½ years.

To all whom it may concern:

Be it known that I, FRANZ YOKEL, of Meriden, in the county of New Haven and State of Connecticut, have invented a new Design for a Table-Top; and I do hereby declare the following, when taken in connection with accompanying drawing, to be a full, clear, and exact description of the same, and which said drawing constitutes part of this specification, and represents a top or face view, the ornamentation represented on one - fourth only, the remaining three-fourths being a duplicate thereof.

This invention relates to a design for a table-top; and it consists in the configuration and ornamentation as shown in the accompanying illustration.

The center represents a rectangular border, and around this border is the representation of lacework, giving the appearance of out-

ward and inward scallops, the inward scallops represented as lying upon or springing from the frame. The scallops at the angles are formed by scrolls, and the intermediate scallop on each side presents a shell-like edge connected to the frame by scrolls, and the scallops on the sides are represented as joined to the scallops at the angles by ornamented scrolls, as shown in the accompanying illustration. 30

I claim—

The design for a table-top, as herein shown and described.

In testimony whereof I have signed this specification in the presence of two subscribing witnesses. 35

FRANZ YOKEL.
